UNITED STATES PATENT OFFICE.

FRANK L. ARGALL, OF SAN JOSE, CALIFORNIA.

DENTAL SWAGING APPARATUS.

No. 821,150.

Specification of Letters Patent.

Patented May 22, 1906.

Application filed October 25, 1904. Serial No. 229,988.

To all whom it may concern:

Be it known that I, FRANK L. ARGALL, a citizen of the United States, residing at San Jose, in the county of Santa Clara and State 5 of California, have invented certain new and useful Improvements in Dental Swaging Apparatus, of which the following is a specification.

This invention relates to an improved 10 swaging device for forming dental plates or crowns, the object of the invention being to provide a strong, simple, and convenient device of this character.

A further object of the invention is to provide 15 means whereby the die on which the plate is to be swaged can be removed intact from the apparatus.

In the accompanying drawings, Figure 1 is 20 a vertical section of the apparatus. Fig. 2 is a plan view thereof. Fig. 3 is a horizontal section of the apparatus. Fig. 4 is a vertical section of the base on the line 4 4 of Fig. 3. Fig. 5 is a vertical section of the flask-cavity with the parts in position for use.

25 Referring to the drawings, 1 represents a suitable base, having formed integral therewith diametrically opposite standards 2, bent inward at the top to support a collar 3, threaded on the inside to receive a threaded 30 retainer 4, which rests upon the upper section 5 of the flask in which the plate is to be swaged. The lower flask-section 6 is laid upon the base 1 and has a circular shoulder 7, which fits within a circular recess 8, formed 35 in the lower edge of the upper flask-section.

The lower flask-section 6 is formed with a cavity 9 to receive the die 10, onto which the plate 11 is to be swaged. This die is a cast 40 of the mouth in fusible metal, the casting of the die being made upon the lower flask-section, so that the under part of the die is run or cast in the cavity 9. It is often the case 45 that after using the die to form the plate the fusible metal is immediately melted over again for other purposes; but, on the other hand, it may also happen that it is desired to

preserve the die, while at the same time using the apparatus for other operations, and the cavity 9 is so formed as to permit this to be 50 done, for it is made with an upwardly-inclined bottom sloping continuously to the surface at one side, as shown at 12, the cavity widening from its deepest portion to the shallow end 12 thereof, as shown, and the 55 sides of the cavity being undercut, as shown at 13. With this construction a die seated

in the cavity on the lower flask-section can without being destroyed be readily removed thereon by giving a gentle tap thereto at the narrow deep end thereof.

60

The retainer 4 is hollow and is threaded internally in its upper portion, as shown at 14, and within the same is screwed a hollow screw 15. A plunger 16, having a head 17, slides through the smooth bore of the hollow 65 screw 15 and has a shoulder 18, against which the bottom of the screw 15 can rest.

The operation of the apparatus is as follows: The die 10 having been cast upon the lower flask-section 6, the plate 11, which is to 70 be swaged to the form of the die, is laid over the die. Then rubber or cloth 20 is laid over the plate. Then a body of paraffin 21 is placed upon the lower flask-section. The upper flask-section having been placed in position, 75 the screw 4 is screwed down to hold the flask so formed firmly together. Then the screw 15 is screwed down into the flask-cavity as far as possible, compressing the paraffin. Then when no further compression can take place 80 by this means the plunger 16 is given a powerful blow, still further compressing the paraffin and separating the shoulder 18 from the bottom of the screw 15. This permits of the screw 15 being screwed down a little far- 85 ther until the lower end thereof meets the shoulder 18, when a blow is given to the plunger, and the screw is again screwed down, and so on, until the paraffin will bear no further compression, and the plate is swaged to 90 the die.

It will be understood that my invention is not limited to the precise form of apparatus herein shown, as the form of the base and the neck and the shape of the flask-sections and 95 of other parts of the apparatus may be varied without departing from the spirit of my invention, nor is my invention limited to the use of paraffin as the deformable material within the flask, as other suitable material 100 may be used.

I claim—

1. In combination with flask-sections, means for firmly holding the two together to form the flask, a screw having a smooth bore, 105 a plunger sliding in said bore and entering the flask-cavity, the plunger having a shoulder engaging the screw to limit its outward movement, the parts being provided with means for enabling the screw to be screwed 110 toward the cavity, substantially as described.

2. In an apparatus of the character described, the combination of upper and lower flask-sections, means for holding said flask-sections together formed with an internally-threaded passage for a screw, a screw screwed into said passage and having a smooth bore, and a plunger sliding in said smooth bore, its inner end entering the flask-cavity and having a shoulder engaging said screw to limit the outward movement of the plunger, substantially as described. 45
3. In an apparatus of the character described, the combination of upper and lower flask-sections, means for holding the flask-sections together, one of said flask-sections having a die-cavity, the bottom of which slopes continuously upward to the surface of the section, whereby the die can be driven transversely out of the cavity, and means 50 for compressing material in the flask-cavity, substantially as described. 55
4. In an apparatus of the character described, the combination of upper and lower flask-sections, means for holding the flask-sections together, one of said flask-sections having a die-cavity, the bottom of which slopes continuously upward to the surface of the section, and the sides of said die-cavity flaring outward toward said shallow portion, whereby the die can be driven transversely out of the cavity, and means for compressing material in the flask-cavity, substantially as described. 60 65
5. In an apparatus of the character described, the combination of upper and lower flask-sections, means for holding the flask-sections together, one of said flask-sections having a die-cavity, the bottom of which slopes upward to the surface of the section, and the sides of said die-cavity being undercut and flaring outward toward said shallow 70 75

portion, whereby the die can be driven out of the cavity, and means for compressing material in the flask-cavity, substantially as described. 45

6. In an apparatus of the character described, the combination of a suitable support having standards and a collar supported by said standards, upper and lower flask-sections on said support, a threaded neck in said collar bearing down upon the upper flask-section and maintaining the flask-cavity closed, said neck being hollow and threaded internally, a screw screwed into said internally-threaded neck and having a smooth longitudinal bore, and a reciprocating plunger in the bore of said screw, substantially as described. 50 55

7. In an apparatus of the character described, the combination of a suitable support having standards and a collar supported by said standards, upper and lower flask-sections on said support, a threaded neck in said collar bearing down upon the upper flask-section and maintaining the flask-cavity closed, said neck being hollow and threaded internally, a screw screwed into said internally-threaded neck and having a smooth longitudinal bore, and a reciprocating plunger having a shoulder engaged by said screw to limit the outward movement of the plunger, substantially as described. 60 65 70

In witness whereof I have hereunto set my hand in the presence of two subscribing witnesses. 75

FRANK L. ARGALL.
